UNITED STATES PATENT OFFICE.

JUSTIN WHITNEY, OF BOSTON, MASSACHUSETTS.

DESIGN FOR AN IRON FRAME FOR UPRIGHT PIANOS.

Specification forming part of Design No. 5,293, dated September 26, 1871.

To all whom it may concern:

Be it known that I, JUSTIN WHITNEY, of Boston, of the county of Suffolk and State of Massachusetts, have invented or produced a new, useful, and ornamental Design for the Metallic String-Frame of an Upright Piano-Forte; and do hereby declare the same to be described in the following specification and represented in the accompanying drawing, of which—

Figure 1 is a front elevation; Fig. 2, a top view; Fig. 3, an end elevation; Fig. 4, a longitudinal and vertical section; Fig. 5, a vertical and transverse section; and Fig. 6, a horizontal section of such frame. Fig. 7 is a rear elevation of it.

In such frame each of the oblique bars A B C has a transverse section, as shown in Fig. 8, they being arranged, with respect to each other and the rest of the frame, in manner as shown. The lower bar D, with the two upright end bars E E, has a somewhat different section, as represented. The upper bar, curved lengthwise and formed in transverse section, as shown, is furnished with two curved flanges, a b.

I claim as my invention—

The piano-forte frame design, substantially as described and represented.

Witnesses: JUSTIN WHITNEY.

R. H. EDDY,
J. R. SNOW.
